DESIGN FOR AN ACCORDION GRILLE

Harry Meyers, New York, N. Y.

Application September 28, 1938, Serial No. 80,126

Term of patent 7 years

To all whom it may concern:

Be it known that I, Harry Meyers, a citizen of the United States residing at New York, in the county of New York, city and State of New York, have invented a new, original, and ornamental Design for an Accordion Grille, of which the following is a specification, reference being made to the accompanying drawing, forming a part thereof.

Fig. 1 is a top plan view of the article showing my design;

Fig. 2 is a front view; and
Fig. 3 is an end view.

The dominant feature of the design resides in the appearance of the front of the grille wherein vertical bars extend from obtusely angled lower edge bars upwardly and around the front rounded corner edge of the grill substantially as shown.

I claim:

The ornamental design for an accordion grille, substantially as shown and described.

HARRY MEYERS.
